(Cl. D4—3)

FIG. 1

FIG. 2

FIG. 3

FIG. 5

FIG. 4

FIG. 6

FIG. 7

FIG. 1 is a front perspective view of a combined display and charging unit for battery operated appliance, showing my new design;

FIG. 2 is a top plan view thereof;

FIG. 3 is a front elevational view thereof;

FIG. 4 is a rear elevational view thereof;

FIG. 5 is a top plan view thereof as viewed in FIG. 4 with the transparent cover portion removed;

FIG. 6 is a right side elevational view thereof as viewed in FIG. 1; and

FIG. 7 is a bottom plan view thereof as viewed in FIG. 1.

The closely spaced parallel lines on flat surface within the two depressions on the top of the cover represent conventional grooves.

The elements shown in broken lines in FIG. 1 are included for illustrative purposes only.

I claim:

The ornamental design for a combined display and charging unit for battery operated appliance, as shown and described.
